CLAIM

The ornamental design for a magnetic tape cassette, as shown and described.

DESCRIPTION

FIG. 1 is a top, front and right side perspective view of a magnetic tape cassette showing our new design; FIG. 2 is a bottom, front and left side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and

FIG. 8 is a rear elevational view thereof.

The window seen in the center of the magnetic tape cassette in FIGS. 1 and 3 is transparent.
